Arthur B. Jenkins,
ATTORNEY.

UNITED STATES PATENT OFFICE.

CHARLES A. BAILEY, OF CROMWELL, CONNECTICUT.

TOY PISTOL.

1,305,335.

Specification of Letters Patent. Patented June 3, 1919.

Application filed October 2, 1918. Serial No. 256,525.

To all whom it may concern:

Be it known that I, CHARLES A. BAILEY, a citizen of the United States, and a resident of Cromwell, in the county of Middlesex and State of Connecticut, have invented a new and Improved Toy Pistol, of which the following is a specification.

My invention relates more especially to that class of toys used for exploding persons or "paper" caps, and an object of my invention, among others, is to provide a toy of this class that shall be extremely simple in its construction and operation and one that may be constructed at a minimum 15 cost.

One form of toy pistol embodying my invention and in the construction and use of which the objects herein set out, as well as others may be attained, is illustrated in 20 the accompanying drawings, in which—

Figure 1 is a view in side elevation of a toy pistol embodying my invention.

Fig. 2 is a similar view looking at the side opposite from that shown in Fig. 1.

Fig. 3 is a view in side elevation of a portion of such pistol with parts broken away to show construction.

Fig. 4 is a top view of my improved pistol.

Fig. 5 is a fragmentary view illustrating 30 a slightly different method of feeding the paper cap strip.

My improved toy pistol, embodying a frame preferably formed of a single piece of cast metal, comprises a handle 5, a receiver 6 and a barrel portion 7. The handle is of the general form of devices of this class, and just forward of the handle is a stop 8 to receive the finger of the operator and stop its movement in the operation of 40 feeding a cap.

One side of the frame is preferably flat, as shown in Fig. 2 of the drawings, and the opposite side is provided with a bordering flange 9. Magazine walls 10—11 and guide 45 lugs 12 extend at right angles to the plane of the frame. The walls 10 and 11 form a magazine chamber 13, the wall 10 extending parallel with the wall 11 as to its upper part and being curved as to its lower part, as shown in Fig. 1 of the drawings. A barrier 14 comprising a lug extending from the back of the wall 10 prevents the fire from an exploding cap gaining access to the unexploded portions of a paper strip 55 and thereby igniting such portions.

A stud 15 projects from the center of the

magazine chamber to receive a roll 16 of a paper strip having the caps formed at intervals therealong in a well known manner. This roll lies within the magazine 60 chamber and within the curved extension of the wall 10 that forms a separator 17. The end of the paper cap strip is projected outside of the curved separator on the wall and below the edge of the frame, the free 65 end of the strip being retained in position by the guide lugs 12 that properly guide it against the wall 10 and to a point above the barrier 14. A carrier plate 18 is mounted for sliding movement against the walls 70 10 and 11. This plate is secured in position at its rear end by a spring supporting rod 19 projecting rearwardly and receiving a spring 20 thrusting with one end against the flange 9 and with its opposite end 75 against the edge of a spring retaining lip 21 from which the rod 19 projects and which lip extends inwardly from the inner side of the carrier plate.

A hammer 22 comprises a lip extending 80 inwardly from the inner face of the plate 18, as shown in Fig. 4. This hammer is in position to strike an anvil formed on the rear side of the wall 10 above the barrier 14, or the free end of the paper strip which is 85 passed between the anvil and said hammer.

The carrier plate 18 is held in place at its forward end by a retainer 24 that is passed through a retaining slot 25 in the frame, the end of the retainer being bent at right angles 90 to that part projecting through the slot 25 and resting against the opposite side of the frame from that on which the carrier plate is located. A retaining notch 26 is formed in the bottom of the slot 25 to receive the 95 retainer 24 and hold the carrier plate in its rearward position against the tension of the spring 20.

In operation the finger of the operator is placed against the trigger 23, projecting 100 from the front end of the carrier plate, and by pressure thereon the carrier plate 18 is moved backwardly, downward pressure of the finger causing the retainer to engage the retaining notch 26 and thus hold the plate 105 in its backward position. When this position of the carrier plate has been reached a continued backward movement of the finger of the operator engages that portion of the paper cap strip underneath the separator 110 17, and said strip is moved backwardly extending the free end upwardly past the

guides 12 and within the firing chamber between the anvil on the wall 10 and hammer 22. The paper strip having thus been positioned for firing operation the finger of the 5 operator may be moved forward to engage the back of the trigger 23 and the slide may thus be pressed upwardly so that the retainer 24 will be disengaged from the retaining notch 26, and the spring 20 will 10 force the carrier plate forward carrying the hammer forcibly against the paper cap and exploding it.

In the form of the device shown in Fig. 5 a mechanical device for feeding the paper 15 strip is shown, this comprising a finger piece 30 pivotally attached to the frame as by means of a bar 31 having a tongue 32 projecting through a slot 33 in the frame and engaging the opposite side of the frame 20 to retain the bar in position.

In accordance with the provisions of the patent statutes, I have described the principles of operation of my invention together with the device which I now consider to represent the best embodiment thereof; but I 25 desire to have it understood that the device shown is only illustrative and that the invention may be carried out by other means.

I claim:—

30 1. A toy pistol embodying a frame having a chamber open on one side, and a plate comprising a part of the operating mechanism of the device, said plate being movably attached to the frame opposite said opening 35 to prevent removal of an object therefrom.

2. A toy pistol embodying a frame having a chamber open on one side, and a plate comprising a part of the operating mechanism of the device, said plate being slidably 40 attached to the frame opposite said opening to prevent removal of an object therefrom.

3. A toy pistol embodying a frame, a plate slidably mounted on the outside of said frame, a hammer carried by said plate, 45 means for securing the plate outside the frame for sliding movement thereon, means to receive the blows of said hammer, and means to operate the plate.

4. A toy pistol embodying a frame, a 50 plate slidably mounted outside of the frame and having an integral retainer projecting through a slot in the frame and resting

against the opposite side of the frame to retain the plate in place, a hammer carried by said plate, means to receive the blows of said hammer, and means for operating the plate. 55

5. A toy pistol embodying a frame, a plate slidably mounted on the outside of said frame, a hammer carried by said plate, a holder projecting from the plate into position to engage a notch in the frame to hold the plate in its backward position, means on the frame to receive the blows of the hammer, and means for forcing the plate forward. 60

6. A toy pistol embodying a frame open on one side, walls projecting from the open side of said frame to form a magazine chamber for a roll of ammunition open on one side of the frame, a plate slidably mounted on said walls to partially close said chamber, a hammer carried by said plate, an anvil to receive blows of the hammer, and means for driving the plate forward. 65

7. A toy pistol embodying a frame open 75 on one side, walls projecting from the open side of the frame to form a magazine chamber for a roll of ammunition, a roll receiving stud projecting from the inner side wall of said chamber, a plate slidably mounted on 80 the edge of said walls to partially close said chamber, an anvil, and a hammer carried by said plate to operate against said anvil.

8. A toy pistol embodying a frame, means upon the frame to receive an ammunition 85 roll with its edge projecting below the lower edge of the frame to position a layer of said roll for access of a human finger to apply pressure thereto, a rest for said layer positioned to receive said layer and the pressure of said finger and along which said finger is moved to feed the layer, an anvil to receive the free end of the strip, and a hammer to operate against said anvil. 90

9. A toy pistol embodying a frame, a separator projecting from one side of the frame to separate the free end of an ammunition roll from the main part thereof, said separator being curved to form a guide for a human finger in moving the free end of said 100 roll forward, an anvil to receive the free end of said roll, and a hammer to operate against said anvil.

CHARLES A. BAILEY.
